VAPORIZING DEVICE FOR LIQUEFIED
GASES

Odd Arnold Hansen, Buffalo, N. Y., assignor to
The Linde Air Products Company, New York,
N. Y., a corporation of Ohio

Application March 1, 1933, Serial No. 659,191

5 Claims. (Cl. 219—33)

This invention relates to a vaporizing device for liquefied gases, and particularly to a vaporizing and heating means for liquid oxygen which employs convection as the heating principle.

5 The invention has for its object generally an improved device of the character indicated which is efficient, economical and readily manufactured.

More specifically, it is an object of the invention to provide a device for heating and vaporizing liquid oxygen which is both efficient and safe from an operating standpoint.

It is also an object to provide a device for vaporizing liquid oxygen discharged from a container, in a manner which reduces operating hazards 15 while the temperature of the oxygen heating parts is substantially at the temperature of the atmosphere, thereby reducing heat leakage to the atmosphere.

It is a further object to provide a device for heating liquid oxygen by convection in which the heat supplying means is relatively distant from the oxygen heating coil and is arranged to effect circulation of the heat conveying medium in counter-current fashion over the oxygen heating 25 coil, whereby a relatively uniform temperature difference is maintained along such coil.

It is a still further object to provide a vaporizing device of the convection type for liquid oxygen heating systems which employs air as the heat 30 conveying medium and is constructed to insure against undue variation in the thermal characteristics of the medium, such as the specific heat capacity and thermal conductivity of the medium.

Other objects of the invention will in part be 35 obvious and will in part appear hereinafter.

The invention accordingly comprises the features of construction, combination of elements, and arrangement of parts, which will be exemplified in the construction hereinafter set forth and 40 the scope of the application of which will be indicated in the claims.

For a fuller understanding of the nature and objects of the invention, reference should be had to the following detailed description taken in connection with the accompanying drawing, in 45 which:

Fig. 1 is a view mainly in elevation showing a container for liquid oxygen having connected thereto a vaporizing device constructed in accordance with the invention;

Fig. 2 is an enlarged vertical section of the vaporizing device taken on the line 2—2 of Fig. 1; and

Fig. 3 is a fragmentary view mainly in elevation, parts being broken away showing further

details in the construction of the vaporizing device shown in Fig. 2.

Referring now to the drawing and particularly to Fig. 1, 10 denotes generally a container for liquefied gas, that shown being of the insulated type, such as is employed for supplying liquid oxygen for industrial consumption. The container stands on a suitable foundation and is provided with a liquid discharge conduit 11 leading from a control panel 12 on the container to a vaporizing device, shown generally at a.

The vaporizing device here employed is adapted to supply a relatively large quantity of heat to the liquid withdrawn from the container, since it is desired not only to cause the liquefied gas 70 to change from the liquid phase into the vapor phase so that the temperature of its vapor phase will be increased a substantial amount above the boiling point of the liquefied gas, but also in a manner that substantially insures against over-heating the parts. To this end, the vaporizing device comprises a substantially closed chamber in which a heat supplying means is located at a distance from a heat absorbing means through which the liquid oxygen passes, the heat being 75 transferred by convection from the supply means to the absorbing means through a suitable heat conveying medium, such as air. In order that

this air may not have its thermal characteristics adversely affected by intermittent operation of 80 the device which would cause expansions and contractions of the air, the vaporizing device is provided with a breathing device 13, which affords communication between the circulating 85 chamber and the outer atmosphere and extracts 90 the moisture from the entering air, whereby substantially dry air alone circulates in the chamber. This breathing device may be of any suitable variety, for example, that shown in the co-pending application of L. I. Dana and G. H. 95 Zenner, Serial No. 306,269, where a depending chamber, open at the lower end, contains a moisture extracting agent, such as calcium chloride, and communicates at the upper end with the chamber to be supplied with dry air; communication here being provided by way of the connection shown at 13'.

The oxygen thus heated passes from the vaporizing device in a manner such that it will not unduly cool operating parts subsequently traversed, for example, a regulating device, shown conventionally at 14, interposed in the consumer's pipe line 15. While it is customary to interpose regulating devices which maintain a desired delivery pressure in the consumer's pipe 110

line, as here shown, it is desired that this regulating device shall be at no time at so low a temperature as to impede the proper functioning of the parts. The use of such devices, however, 5 comprises no part of the present invention, but is shown here merely as exemplary of an operating device which is protected against undesired temperatures.

The construction of a preferred form of vaporizing device, depicted somewhat symbolically in 10 Fig. 1, is shown more in detail in Figs. 2 and 3. Here, a casing 16 is employed which is preferably of the double-walled variety and has heat insulation interposed. Within this casing is disposed 15 a transverse barrier 17, which does not quite extend to the bottom of the casing and stops short of the top thereof. In this manner, a circulation passage is provided about the barrier in which the heat conveying medium circulates in ascending and descending currents.

The means for supplying heat may be of any 20 convenient form and character, but is preferably an electric heating means 18, which is here shown as comprising a plurality of superposed banks of 25 electric heating elements in which the heating elements are directly exposed to the air. Each of these banks as seen from Fig. 3 comprises a pair of rod-like horizontal insulating supports 20 and 20' which support a plurality of turns 19 30 of a resistance. These turns or elements may be connected electrically in any suitable manner adapted to supply sufficient electric current to accomplish the desired heating effect. The means for supplying the heating current to the 35 heating elements of the vaporizer *a* is shown generally at 21 in Fig. 1 and include an electric control panel 22.

Heat absorbing means, traversed by the gas 40 material to be heated and vaporized, are also disposed in the casing. The heat absorbing means here shown comprises a plurality of coils 23 connected to be traversed by the gas material successively which are provided with heat 45 conducting fins 24 that divide the circulating medium into small streams and quickly conduct the abstracted heat to the material within the coils 23. The inlet of the coils is connected to the conduit 11 at a point in a relatively cold portion of the descending current of circulating 50 medium, while the discharge conduit 15 is connected to the coils at a point which is in a relatively warm portion of the descending current of circulating medium. By this arrangement, it is seen that the coils employ the counter-current 55 method of heating the gas material traversing the same and insure a relatively uniform difference along the coils between the temperature within the coils and that of the adjacent medium on the exterior of the same. The coils 23, 60 while they may be in general located anywhere in the path of the circulating medium, are preferably disposed in a region which is at some distance from the heat radiating means 18. Accordingly, the coils 23 and means 18 are shown 65 on the opposite side of the barrier 17, the means 18 being disposed at the beginning of an ascending current of circulating medium while coils 23 are at the beginning of a descending current.

In operation, it is seen that gas material is 70 withdrawn from the container 10 through the conduit 11 and passed to the heat absorbing coils in the vaporizer *a*. Here, the coils are subject to the heating influence of the circulating medium and abstract quickly the heat therefrom 75 as pointed out above. It is seen that by reason

of the vertical arrangement of the heat radiating means and heat absorbing means and by their disposition on opposite sides of the barrier 17, a rapid circulation of this medium is effected, since it is quickly cooled by the heat absorbing coils and passed to the lower end of the casing *a*, where it is again heated by the heat radiating means 18 and caused to rise under the influence of the field of gravity. The casing *a* being substantially closed, permits no ingress of atmospheric air from the outside, except through the drying trap 13 provided. Thus, the liability of moisture depositing upon the coils 23 and interfering with the heating effect is substantially eliminated, the air circulated being substantially dry. The temperature to which this air is heated is preferably not substantially different from that of the atmosphere; and whether the casing 16 be of the insulating variety or not, it is seen that, by the maintenance of a relatively low temperature for the heat transfer medium, heat leakage from the system is reduced substantially to a relatively small amount.

While the heating means here described is a resistance type of electric heater, it is contemplated that other types of electric heaters may also be employed, for example, induction heaters. Where induction heaters are employed, the inducing winding may, with advantage, be so placed as to induce the heating current directly in the 105 coils of the heat absorbing means.

Since certain changes may be made in the above construction and different embodiments of the invention could be made without departing from the scope thereof, it is intended that all matter 110 contained in the above description or shown in the accompanying drawing shall be interpreted as illustrative and not in a limiting sense.

Having described my invention, what I claim as new and desire to secure by Letters Pat- 115 ent, is:

1. In a vaporizing device for liquefied gas, the combination comprising a substantially closed casing having an unimpeded circuitous passage therein about which a gaseous heat conveying 120 medium is circulated by convection, a heat absorbing means adapted to be traversed by the gas material to be elevated in temperature disposed in one portion of said passage, and means for heating said medium disposed in said passage in 125 a position relative to said heat absorbing means such as to induce convection under the influence of gravity.

2. In a vaporizing device for liquefied gases, the combination comprising a substantially closed 130 casing having an independent barrier stopping short of its upper and lower ends about which barrier air is adapted to circulate freely, heat absorbing means including a coil traversed by the gas material to be elevated in temperature dis- 135 posed on one side of said barrier, and heat radiating means disposed in said casing on the other side of said barrier and at such a distance from said heat absorbing means as to induce circulation of said air under the influence of gravity. 140

3. In a vaporizing device for liquid oxygen, the combination comprising a substantially closed insulating casing having a barrier disposed in a substantially vertical plane extending across said casing but stopping short thereof at its upper and 145 lower ends about which barrier air is adapted to circulate, heat absorbing means including a coil traversed by the oxygen to be elevated in temperature disposed in said casing on one side of said barrier adjacent the upper end, and heat radiat- 150

ing means disposed in said casing on the other side of said barrier adjacent the lower end.

4. In a vaporizing device for liquid oxygen, the combination comprising a substantially closed insulated casing having a barrier stopping short of its upper and lower ends and positioned to form a passage of relatively uniform cross-sectional area through which air is adapted to circulate, heat absorbing means including a plurality of coils arranged to be traversed successively by the oxygen to be elevated in temperature disposed in said casing with the inlet in a relatively cold portion of the circulation passage and the outlet in a relatively warm portion of said circulating passage, and electric heating elements disposed in said casing on the other side of said barrier substantially below said heating coils.

5. In a vaporizing device for liquid oxygen, the combination comprising a substantially closed in-

sulated casing, a barrier disposed in a substantially vertical plane extending across said casing but stopping short thereof at its upper and lower ends, means for admitting dehydrated air from the atmosphere to said casing for circulation as a heat conveying medium about said barrier, a heat absorbing means including a plurality of tubular coils arranged to be traversed by the oxygen to be elevated in temperature flowing in succession therethrough and disposed in said casing on one side of said barrier adjacent its upper end, an inlet connection for said coils leading to the substantially lowest point thereof, an outlet connection for said coils leading from the substantially highest point thereof, and electric heating means disposed in said casing on the other side of said barrier adjacent the lower end thereof.
